HOUSEHOLD CLEANING CADDY CART
OR THE LIKE

Irene S. Bell, 4674 Brewster Drive,
Tarzana, Calif. 91356

Filed Dec. 10, 1965, Ser. No. 143

Term of patent 14 years

(Cl. D14—3)

FIGURE 1 is a side elevational view of a household cleaning caddy cart or the like showing one species of my new design;

FIGURE 4 is a front elevational view of a portion of a second species thereof, the remaining portions being substantially identical to those shown in the previous figures; and

FIGURE 5 is a perspective view of a portion of a third species which differs from the previous species only by the weaving pattern of the woven wire baskets.

I claim:

The ornamental design for a household cleaning caddy cart or the like, substantially as shown and described.
